UNITED STATES PATENT OFFICE.

JAMES STANLEY ATKINSON, OF LONDON, ENGLAND, ASSIGNOR, BY MESNE ASSIGNMENTS, TO OPEN HEARTH COMBUSTION COMPANY, OF CHICAGO, ILLINOIS, A CORPORATION OF DELAWARE.

REVERSIBLE REGENERATIVE FURNACE.

Application filed August 8, 1921, Serial No. 490,697, and in Great Britain September 22, 1913.

(GRANTED UNDER THE PROVISIONS OF THE ACT OF MARCH 3, 1921, 41 STAT. L., 1313.)

My invention relates to improvements in reversible regenerative furnaces.

An object of the present invention is to improve the construction and operation, of 5 reversible regenerative furnaces such as are used in the manufacture of steel, glass, and the like.

These furnaces, as usually constructed, have gas and air passages and ports, situated at each end of the furnace hearth. 10 The incoming gas and air, having been heated in the regenerative chambers, pass into the furnace proper through the set of ports, at one end of the furnace hearth and, 15 when the furnace is reversed, they pass in by the set of ports at the other end of the furnace hearth. The products of combustion pass out of the furnace proper by the set of ports and passages opposite those at 20 which the gas and air enter. Owing to the outgoing products of combustion passing from the furnace proper at a very high temperature, the material at the ports is rapidly burnt back, making it necessary to 25 frequently stop the furnace for repairs, to enable the proper direction of the incoming gas and air to be maintained, and moreover the said burning back causes the place where combustion takes place in the furnace 30 proper to gradually recede, this resulting in loss of efficiency and reduced speed of action.

To overcome these objections, I provide, 35 at each end of the furnace hearth, and separate from the gas and air passages and ports, an outlet passage, or outlet passages, for the products of combustion, the entrance to which passage, or passages, should be in advance of the gas and air ports. In this 40 improved construction the products of combustion, passing from the furnace proper, do not impinge directly on the material at the gas and air ports, so that these are more durable. Any known, or suitable arrangement 45 of valves is provided for controlling the flow of gas and air from the regenerative chambers through to the air and gas passages and ports, and the flow of the products of combustion from the furnace 50 proper to the regenerative chambers.

I will describe, with reference to the ac-

companying drawing, a furnace in accordance with this invention. Only one half of the furnace is shewn, it being understood of course that the other half is similar to 55 the half shewn.

Figure 1 is a longitudinal section of one longitudinal half of the furnace. Figure 2 is a section on the line A. B. Figure 1; 60 Figure 3 is a section on the line C. D. Figure 1; Figure 4 is a section on the line E. F. Figure 1; Figure 5 is a section on the line G. H. Figure 4; and Figure 6 is a section on the line I. J. Figure 4.

At each end of the furnace hearth there 65 are gas and air passages and ports (marked 1 and 2 respectively for supplying the mixture of gas and air necessary for combustion in the furnace proper. Gas and air from passages 1 and 2 are mixed in a 70 port 1^a prior to introduction into the furnace hearth. As shown in Figures 3 and 4 the mixing port 1^a is relatively narrow as compared with the width of the furnace 75 hearth.

At each end of the furnace hearth are 80 outlets (separate from the burner, or burners consisting of the gas and air ports 1 and 2 and with their openings in advance thereof) those shewn being marked 3, these outlets being controlled by valves 4 in the 85 passages 5 by which the said outlets communicate with the regenerative chambers, which are indicated at 6, the valves 4 also controlling the flow of heated gases for combustion so that when the said valves are raised to their upper position there is communication between the outlet passages 3 and the regenerative chambers 6 and when the said valves are in their lower position, 90 there is communication between the gas and air passages 1 and 2 and the said regenerative chambers. 7 is a slag chamber between the outlet passages 3 and the passages 5.

The furnace is provided with appliances 95 for reversal and other necessary appliances, or arrangements, which may be similar to those in use in other reversible regenerative furnaces, and the invention is not confined to the precise arrangement of the burners and gas and air inlets thereof as shewn, the 100 essential feature of this invention being the

arrangement at each end of the furnace hearth of the outlet, or outlets, separate from the inlet ports and passages as hereinbefore explained.

5 I am aware that it has been proposed to arrange a furnace with two communicating hearths and to provide in each an outlet passage separate from the inlet passage, so that the two hearths can be used alternately and the residual heat in either be utilized in the other, and to such an arrangement I make no claim.

What I claim as new and desire to secure by Letters Patent in the United States, is:

15 1. An open-hearth furnace comprising, in combination, a hearth, a combined fuel and air port at each end of the furnace of relatively small width as compared with the hearth, regenerative chambers having communication with said ports, additional channels leading from the regenerative chambers to the interior of the furnace adjacent the ends thereof, and means for causing the entire air passing through the regenerative 20 chamber at the inlet end of the furnace to pass through the combined fuel and air port.

2. An open-hearth furnace comprising, in combination, a hearth, a combined fuel and air port at each end of the furnace of relatively small width as compared with the hearth, regenerative chambers having communication with said ports, additional channels leading from the regenerative chambers to the interior of the furnace adjacent the ends thereof, means for causing the entire air passing through the regenerative chamber at the inlet end of the furnace to pass through the combined fuel and air port, and means for preventing the flow of the products of combustion through the combined fuel and air port at the outlet end of the furnace and causing the same to pass through the additional channel into the regenerative chamber.

45 3. An open-hearth furnace comprising, in combination, a hearth, a regenerative chamber at each end, a combined fuel and air port communicating with each end of the furnace of relatively small width as compared with the hearth, and with the respective regenerative chamber, additional channels connecting the regenerative chambers with the furnace adjacent the two ends, and a throttle-valve in each additional channel.

55 4. In reversible regenerative furnaces, the provision at each end of the furnace hearth, of an outlet passage, for the products of combustion, the said outlet passage, being separate from the inlet gas and air passages and ports; substantially as hereinbefore explained.

5. In reversible regenerative furnaces, the provision at each end of the furnace hearth, of an outlet passage, for the products of com-

bustion, the said outlet passage, being separate from the inlet gas and air passages and ports and the entrances to the said outlet passage being in advance of the inlet gas and air ports; substantially as hereinbefore explained.

6. A reversible regenerative furnace having a hearth, a regenerative chamber for each end thereof, a passage for conducting fluid from each of said regenerative chambers to said hearth and a separate outlet passage to each of said chambers.

7. A reversible regenerative furnace having a hearth, a regenerative chamber for each end thereof, a passage between each of said chambers and said hearth for conducting fluid to said hearth and other passages between said hearth and said chambers and means for selectively interrupting communication through said passages.

8. A reversible regenerative furnace having a furnace hearth, a regenerator for each end of said furnace, passages for conducting air from each of said regenerators to said hearth, separate outlet passages from each end of said hearth to afford communication with the corresponding regenerators and means for interrupting communication through said outlet passages.

9. In a reversible regenerative furnace, a passage connecting the furnace and regenerator and means in said passage at a point remote from the furnace chamber adapted to control fluid flow through said passage.

10. In a reversible regenerative furnace, passages connecting each end of the furnace with the associated regenerators, and valves located in said passages at a point between the furnace and regenerators distant from the furnace chamber adapted to control fluid flow through said passages.

11. In an open hearth furnace, regenerative chambers, slag pockets, passages connecting the regenerative chambers and slag pockets, passages connecting the slag pockets and furnace ports, and means for controlling the flow from the regenerators to the slag pockets.

12. In an open hearth furnace, regenerative chambers, slag pockets, passages connecting the regenerative chambers and slag pockets, passages connecting the slag pockets and furnace ports, and means adapted to close off the passages connecting the regenerators and the slag pockets.

13. In an open hearth furnace, a plurality of regenerative chambers at each end of the furnace, a slag pocket connected by passages to each regenerator, and dampers controlling certain of said passages.

Signed at London, England, this 18th day of July, 1921.

JAMES STANLEY ATKINSON.
